CONDENSATE DRAIN SYSTEM FOR STEAM ENGINES

Joseph F. Griffin, Hammond, and Ralph G. Skoog,
 Crown Point, Ind., assignors to Combustion Engineering-Superheater, Inc., a corporation of
 Delaware

Application January 25, 1947, Serial No. 724,454

11 Claims. (Cl. 105—37)

1

The present invention relates to hydraulic pumps and particularly to an automatic drain system for the steam cylinders of a locomotive feed water pump of the reciprocating type.

When a water pump or other apparatus driven by a reciprocating steam engine is stopped after operating, quantities of steam remain in the engine cylinders and condense. Conventionally, the engine cylinders are provided with vent cocks that are opened automatically as by a spring when the engine stops. These however do close by steam pressure as soon as the engine starts and hence do not remain open long enough to permit ejection of the condensate from above the pistons by reciprocation of the latter. This condensate forms a body of water in the cylinders and provides a hammer effect when the pistons are again reciprocating with the result that the pressure built up frequently causes deterioration to and destruction of the top head gaskets for the steam cylinders. The material cost of replacing these gaskets in and by itself is not serious but considerable labor is required to take off the cylinder heads and replace the gaskets and where the pump supplies feed water to a locomotive boiler the necessity of holding the engine out of service until there is an opportunity to perform this rather substantial job is a serious matter. Conventional drain cocks on the cylinders would not be satisfactory on a locomotive feed water pump since as will be apparent it would be impractical for the engineman to climb out on the running board and open the drain cocks preliminary to starting of the pump and then close them after the condensate has been ejected by the reciprocation of the steam pistons.

Likewise the spring actuated automatic check valves for this purpose which would be lifted open by means of springs and close under steam pressure would not prove satisfactory because such valves would open and close with each reversal of the pump. Drain passages from the top to the bottom portions of the cylinders through the pistons are also impractical.

The present invention has for its object the provision of an automatic drain system for the steam cylinders of a locomotive feed water pump of the reciprocating type which will assure that the engineman takes positive action to see that the piston cylinders are properly drained.

In its preferred form the drain system contemplated by the present invention has automatic devices which assure proper draining of the cylinders and the system is rendered fool-proof in that the pump will not operate in a manner satis-

2

factory to the engineman unless he takes the required steps to assure that the drain system automatically performs its function.

The invention will be best understood upon consideration of the following detailed description of several illustrative embodiments thereof when read in conjunction with the accompanying drawings in which:

10 Figure 1 is a diagrammatic view of a drain system for the steam cylinders of a locomotive feed water pump embodying the present invention;

Figure 2 is a plan view of a multiple drain valve unit for the steam cylinders of the pump;

15 Figure 3 is a sectional view of a drain valve on the line 3—3 in Figure 2;

Figure 4 is a sectional view of a control valve that may be utilized in the system shown in Figure 1;

20 Figure 5 is a diagrammatic view similar to Figure 1 illustrating a preferred embodiment of the automatic drain system in accordance with the present invention;

Figure 6 is a sectional view of the control valve forming part of the system illustrated in Figure 5;

Figure 7 is a sectional view of a preferred form of multiple drain valve;

Figure 8 is a transverse sectional view on the line 8—8 in Figure 7.

25 In Figure 1 the numeral 10 designates a locomotive feed water pump of the reciprocating type which draws water from the tender through the suction line 12 and discharges it through the delivery line 14 into the locomotive boiler. The pump 10 is operated by a vertically arranged reciprocating steam engine, designated as a whole by the numeral 16, which is supplied with steam from the turret 18 of the locomotive boiler through the steam line 20, 21 subject to the manually operated pump throttle valve 22 which is mounted in the locomotive cab.

30 The upper and lower ends of the cylinders of the steam engine 16 are tapped for the provision of condensate drain pipes 24 and 26, respectively, leading to a multiple drain valve 30 shown in detail in Figures 2 and 3 so that condensate may flow from the cylinders into the chamber 32 of the valve 30 and out through the valve port 34 into the condensate pipe 36 to be discharged to the track. When the pump is in operation the valves 38 of which there is one for each pipe 24, 26, are maintained off the valve seats 39 around ports 34 by the springs 40 acting on the valve stem 42. To close the valves 38 against the force of their springs 40, steam to act on pistons

35

44 integral with the valves 38 is supplied to the chambers 46 through a conduit 47, 48, which is connected into the pump steam line 20 between throttle 22 and pump 16 and has control valve 50 of the globe type therein which also is mounted in the locomotive cab.

Assuming that it is desired to place the pump in operation to supply water to the boiler; the pump throttle 22 is in closed position having been closed when previously stopping the pump and the control valve 50 also is in closed position, provided the engineman has properly performed his duties. Under these conditions the valve or valves 38 are open and any condensate remaining in the bottom portions of the steam cylinders could drain through the pipes 26 into the drain discharge pipe 36. To place the pump in operation the throttle valve 22 is opened to supply steam to the engine 16 and as the pistons thereof reciprocate any condensate remaining in the top portion of the cylinders is forced therefrom in the first few pump strokes and passes through the piping 24 to the open drain valves 38 and out through the pipe 36. After the condensate has been forced from the engine cylinders each reciprocation of its pistons will cause an amount of steam to blow out through the drain discharge pipe 36 past the drain valves 38 which are now in open position and the noise of the escaping steam should draw the attention of the engineman to this fact. The engineman noting this noise and the attendant waste of steam opens the control valve 50 admitting steam from the line 21 on the down stream side of throttle 22 to the multiple drain valve cylinders 46 with the result that the valves 38 are shifted to the right in Figure 3 on to their seats 40 to be held by steam pressure and close the escape ports 34.

The arrangement described above provides for effectively draining the steam cylinders of the pump of condensate which forms after a period of operation of the pump provided the drain valves 38 are opened after the pump stops and remain in this position for at least a short period after the pump is again placed in operation. Even though the engineman neglects to close the control valve 50 as well as the pump throttle 22 the steam pressure in the drain valve cylinders 46 would bleed off through the conduit 48 past the open valve 50 and conduit 47 into the down stream side 21 of the pump steam line and through the pump cylinders thus relieving the pressure so that the springs 40 act to open the drain valves 38.

However, if the engineman on stopping the pump allows the control valve 50 to remain opened, the opening of the throttle valve to start the pump would simultaneously supply steam past the open control valve 50 to the drain valve piston cylinders 46 through the conduit 47, 48 thereby causing closing of the drain valve 38 promptly upon starting of the pump and possibly before the reciprocation of the engine pistons ejected condensate from its cylinders. To provide a fool proof system and guard against the possibility of the engineman overlooking closing the control valve it is desirable that the opening and closing of the drain valves 38 be rendered as fully automatic as possible. This additional feature for full automatic operation is shown in the embodiment of the invention illustrated in Figures 4 and 8.

In Figure 4 the numeral 52 designates as a whole an automatic control valve which may be substituted for the globe valve 50 in Figure 1.

Its construction assures that the control and drain valves are in proper condition to assure draining of the pump steam cylinders subsequent to stoppage of the pump although the engineman may overlook shutting the control valve again after he has once operated it to close the drain valves when starting the pump. With this form of control valve the engineman upon noting the blowing of steam through the drain discharge pipe 36 after starting the pump effects closing of the drain valves 38 by operating a lever 54 to move the valve member 56 from its seat 57 against the action of spring 58. As the stem 60 of valve 56 is retracted a collar 62 thereon is drawn rearwardly so that it becomes positioned behind a latch member 64 projecting from the valve casing. The latch 64 is projected against the force of a spring 66 when steam pressure is admitted, upon opening pump throttle 22, to a chamber 72 in which the piston 70 fits loosely so steam may enter from the body cavity 68 of valve 52.

When the pump is at rest the drain valves 38 are in open position so that upon opening the throttle 22 to start the pump the reciprocation of the pistons in the cylinders of engines 16 forces any remaining condensate therefrom. At this time the control valve 56 is held to its seat by the spring 58 and upon opening of throttle 22 the admission of steam through the pipe 47 into the chamber 68 of the control valve builds up pressure in the space 72 behind the piston 70 causing the latch pin 64 to be projected from the valve housing. So long as the drain valves 38 remain open steam blows from the drain discharge pipe 36 until the engineman takes note of this fact and operates the lever 54. Thereupon control valve 56 is drawn away from its seat 57 against the action of spring 58. The operation of lever 54 in retracting the valve stem 60 causes the collar 62 thereon to move to the right raising the latch pin 64 against the steam pressure on its piston 70.

As the collar moves to the right beyond the latch pin the steam pressure acts on piston 70 to again project the latch pin 64 into locking position at the left of collar 62 thus holding the control valve 56 off its seat. Steam pressure then being supplied to the piston cylinders 46 for the drain valves 38 moves them to closed position and holds them there so long as the throttle valve 22 is open. Upon closing of the throttle valve 22 to stop the pump pressure in the chamber 68 and piston cylinder 72 of the control valve 52 is bled off through the piping 47 and steam line 20 to the pump cylinders so that the spring 66 becomes effective to retract the latch pin 64 thereby releasing valve stem 60 so that the spring 58 may seat the control valve 56. The steam pressure in the piston cylinders 46 for the drain valves 38 is similarly relieved of pressure so that the springs 40 may open the drain valves 38 and condition the system for draining the engine cylinders when the pump is started again.

Instead of utilizing a mechanical latch to hold it in open position the control valve 80 illustrated in Figure 6 is maintained in open position by steam pressure passing therethrough. When the handle 82 is drawn to the right to move the valve 84 off its seat for supplying steam through the piping 47, 48 to close the drain valves 38, steam flows through an axial passage 86 in the valve stem from the chamber 85 for the valve 84 and through radial passages 87 into a piston cylinder 88 where it acts upon the piston 90 to hold the

valve 84 off its seat. This movement of the piston 90 also moves a vent valve 92 against its seat 93 shutting off communication with a vent pipe 94 through the intermediate chamber 95. Thus, when after starting the pump the engineman notices the blowing off of steam and opens the control valve 64 to supply steam to effect closing of the drain valves 38, the pressure of steam in valve chamber 85 being communicated through the axial and radial passages 86, 87 to piston 90 holds the control valve 84 open. When the throttle valve 22 is closed the bleeding of steam from the chambers 85 and 88, simultaneous with bleeding of the piston cylinders 46 for the drain valves 38 to allow the latter to close, permits the spring 96 to act to close the control valve 84 as the pressure in chamber 88 is relieved.

Figures 7 and 8 illustrate a simplified form of drain valve 100 in which a single valve member 102 is utilized to control communication between the several drain lines 24, 26 leading from the engine cylinders and the condensate discharge conduit 36. The various drain lines 24, 26 are connected in circumferentially spaced relation to the central chamber 103 which leads past the valve seat 104 to an outlet chamber 105 into one side of which the drain line 36 is tapped. A vent pipe 111 is provided for venting the valve casing. When the control valve is opened by the engineman for admitting steam to the piping 48 to cause closing of the drain valve the steam acts on the piston portion 106 of the valve member 102 to move it against its seat 104 against the resistance of a spring 107 and cuts off communication between the chamber 103 and the chamber 105 from which latter the drain pipe 36 leads. Simultaneous with the seating of the valve member 102 the piston portion 108 thereof closes off ports 109 in a sleeve 110 which serves as a guide for the valve 102, and its piston 106, the ports 109 being in alignment with the drain pipe connections 24, 26. Upon closing of the throttle valve pressure against piston 106 is relieved through the conduit 48, 47 and the spring 107 thereupon becomes effective to move the valve member 102 from its seat 104 thereby restoring the drain valve to condition for effecting drainage of the engine cylinders when the pump is again started.

To recapitulate: (1) When the engineman opens the throttle to start the pump condensate is discharged from the cylinders of its engine and then steam blows out through the drains attracting the attention of the engineman. (2) The engineman then opens the control valve which supplies steam to close the drain valves. (3) With the pump in operation the drain valves are held closed by steam pressure admitted by the control valves which remain open. (4) When the pump is stopped by closing its throttle the drain valves open under pressure of their springs as steam bleeds from the piston chambers of the related pistons. (5) In the embodiment of Figures 1 to 3 the engineman to assure continued proper operation must close the control valve as well as throttle valve when stopping the pump. (6) In the embodiments of Figures 4 to 8 such further attention is not required since the control valves close automatically when the pump stops thus assuring that the drain valves will not be closed inadvertently before condensate is discharged. (7) By compelling the engineman to take action to stop the annoyance and waste due to steam blowing off through the drain lines proper draining of the pump engine cylinders is assured and

the automatic release of the mechanical or pressure latch for the control valves in form Figures 3 to 8 positively assures proper sequence of events for continuous operation

5 Although specific embodiments of the invention have been shown and described in detail herein it is to be understood that many changes and embodiments may be made without departing from the invention and therefore it is desired and intended to include all such changes and embodiments within the scope of the appended claims.

What we claim is:

1. In a locomotive feed water system having a pump driven by a reciprocating steam engine and a steam line provided with a throttle valve in the locomotive cab for regulating the operation of said engine and pump, condensate drain pipes connected into the ends of the cylinders of said engine, a condensate discharge pipe connected to said drain pipes, normally open drain valve means interposed between said drain pipes and said discharge pipe, means operable by steam pressure in said line, when said throttle is open to operate said pump, for closing said drain valve means; and manipulative means located in the locomotive cab operative to render said means for closing said drain valve means effective to close said valve means and maintain it closed during operation of said pump.

2. In a locomotive feed water system having a pump driven by a reciprocating steam engine and a steam line provided with a throttle valve in the locomotive cab for regulating the operation of said engine and pump, condensate drain pipes connected into the ends of the cylinders of said engine, a condensate discharge pipe connected to said drain pipes, drain valve means interposed between said drain pipes and said discharge pipe, means acting to normally maintain said valve means in open position, steam actuated operating means for moving said drain valve means to closed position; and a conduit connecting said operating means to said steam line at a point between said engine and the throttle therein; a control valve located in the locomotive cab and interposed in said conduit adapted when in closed position to cut off flow of steam to said operating means for closing said discharge valve means, and means subject to the opening of said throttle for maintaining said control valve in open position during periods when said throttle is open and said pump is in operation.

3. In a locomotive feed water system having a pump driven by a reciprocating steam engine and a steam line provided with a throttle valve in the locomotive cab for regulating the operation of said engine and pump, condensate drain pipes connected into the ends of the cylinders of said engine, a condensate discharge pipe connected to said drain pipes, drain valve means interposed between said drain pipes and said discharge pipe, means acting to normally maintain said valve means in open position, steam actuated operating means for moving said drain valve means to closed position; and a conduit connecting said operating means to said steam line at a point between said engine and the throttle therein; a control valve located in the locomotive cab and interposed in said conduit adapted when in open position to permit flow of steam to said operating means for closing said discharge valve means and means automatically operative to hold said control valve in open position during periods when said throttle is open and said pump is in operation.

4. In a locomotive feed water system having a pump driven by a reciprocating steam engine and a steam line provided with a throttle valve in the locomotive cab for regulating the operation of said engine and pump, condensate drain pipes connected into the ends of the cylinders of said engine; a condensate discharge pipe connected to said drain pipes, drain valve means interposed between said drain pipes and said discharge pipe, means acting to normally maintain said valve means in open position, steam actuated operating means for moving said drain valve means to closed position; and a conduit connecting said operating means to said steam line at a point between the said engine and the throttle therein; a control valve located in the locomotive cab and interposed in said conduit adapted when in open position to permit flow of steam to said operating means for closing said control valve; and locking means associated with said throttle valve and said control valve for maintaining the latter when opened in such condition so long as said throttle is open and for causing it to close upon closing said throttle.

5. In combination with a reciprocating steam engine having a throttle regulated steam line for supplying the latter, condensate drain pipes connected into the ends of the cylinders of said engine, a condensate discharge pipe connected to said drain pipes, drain valve means interposed between said drain pipes and said discharge pipe, means acting to maintain said valve means in open position, fluid actuated operating means for closing said valve means; and a conduit for supplying fluid to said valve operating means; a control valve in said fluid conduit adapted when closed to cut off the supply of fluid to said operating means for closing said drain valve means, manipulative means for opening said control valve; and means subject to opening of said throttle operative to hold said control valve in open position during operation of said engine.

6. In combination with a reciprocating steam engine having a throttle regulated steam line for supplying the latter, condensate drain pipes connected into the ends of the cylinders of said engine, a condensate discharge pipe connected to said drain pipes, valve means interposed between said drain pipes and said discharge pipe, means acting to maintain said valve means in open position, fluid actuated operating means for closing said valve means; and a conduit for supplying fluid to said valve operating means; a control valve in said fluid conduit adapted when open to supply fluid to said operating means for closing said drain valve means; and means operative to hold said control valve in open position during operation of said engine.

7. In combination with a reciprocating steam engine having a throttle regulated steam line for supplying the latter, condensate drain pipes connected into the ends of the cylinders of said engine; a condensate discharge pipe connected to said drain pipes, valve means interposed between said drain pipes and said drain discharge pipe, means acting to maintain said valve means in open position, fluid actuated operating means for closing said valve means; and a conduit for supplying fluid to said valve operating means; a control valve in said fluid conduit adapted when open to permit the flow of fluid to said operating means for closing said drain valve means; steam actuated means associated with said throttle valve and said control valve for maintaining the latter when opened in such condition when supplied

with steam so long as said throttle is open, and means for causing said control valve to close upon closing said throttle.

8. In combination with a reciprocating steam engine and a steam line provided with a throttle valve for regulating its operation, condensate drain pipes connected into the ends of the cylinders of said engine; a condensate discharge pipe connected to said drain pipes, valve means interposed between said drain pipes and said discharge pipe, means acting to normally maintain said valve means in open position, operating means for moving said discharge valve means to closed position; and a conduit connecting said operating means to said steam line at a point between said engine and the throttle therein; a control valve in said conduit adapted when in open position to permit steam flow to said operating means for closing said discharge valve; a steam actuated piston and cylinder therefor associated with said control valve and operative to hold the latter in open position; and a connection between said piston cylinder and said conduit at a point intermediate said discharge valve operating means and said throttle for supplying steam to operate said piston to automatically maintain said control valve in its open position.

9. In combination with a reciprocating steam engine and a steam line provided with a throttle valve for regulating its operation, condensate drain pipes connected into the ends of the cylinders of said engine, a condensate discharge pipe connected to said drain pipes, valve means interposed between said drain pipes and said discharge pipe, means acting to normally maintain said valve in open position, operating means for moving said discharge valve means to closed position; and a conduit connecting said operating means to said steam line at a point between said engine and the throttle therein; a control valve in said conduit adapted when in open position to permit steam flow to said operating means for closing said discharge valve; a steam actuated piston and cylinder therefor associated with said control valve and operative to hold the latter in open position; a connection between said piston cylinder and said conduit at a point intermediate said discharge valve operating means and said throttle for supplying steam to operate said piston to automatically maintain said control valve in its open position; and means operative upon closing of said throttle for closing said control valve.

10. In combination with a reciprocating steam engine and a steam line provided with a throttle valve for regulating its operation, condensate drain pipes connected into the ends of the cylinders of said engine, a condensate discharge pipe connected to said drain pipes, valve means interposed between said drain pipes and said discharge pipe, means acting to normally maintain said valve means in open position, operating means for moving said discharge valve means to closed position; and a conduit connecting said operating means to said steam line at a point between said engine and the throttle therein; a control valve in said conduit adapted when in open position to permit steam flow to said operating means for closing said discharge valve; a steam actuated piston and cylinder therefor associated with said control valve and operative to hold the latter in open position; a connection between said piston cylinder and said conduit at a point intermediate said discharge valve and said throttle at a point intermediate said throttle and

valve operating means for supplying steam to operate said piston to automatically hold said control valve when moved to its open position, said piston cylinder being automatically vented through said conduit upon closing of said pump throttle; and means operative upon venting of said piston cylinder for closing said control valve.

11. In combination with a reciprocating steam engine and a steam line provided with a throttle valve for regulating its operation, condensate drain pipes connected into the ends of the cylinders of said engine, a condensate discharge pipe connected to said drain pipes, valve means interposed between said drain pipes and said discharge pipe, means acting to normally maintain said valve means in open position, operating means for moving said discharge valve means to closed position; and a conduit connecting said operating means to said steam line at a point between said engine and the throttle therein; a control valve in said conduit adapted when in open position to permit flow of steam to said operating means for closing said discharge valve means; latching means associated with said control valve for holding it in open position; a steam actuated piston and cylinder therefor acting on

said latching means to maintain it in locking position; a connection between said conduit and said piston cylinder at a point between said throttle and control valve for supplying steam to the cylinder; and means operative upon closing of said throttle for closing said control valve.
